UNITED STATES PATENT OFFICE.

RALPH BAGGALEY, OF PITTSBURG, PENNSYLVANIA.

APPARATUS FOR MINING.

No. 802,348.

Specification of Letters Patent.

Patented Oct. 17, 1905.

Original application filed May 25, 1904, Serial No. 209,622. Divided and this application filed December 5, 1904. Serial No. 235,416.

To all whom it may concern:

Be it known that I, RALPH BAGGALEY, of Pittsburgh, in the county of Allegheny and State of Pennsylvania, have invented new and useful Apparatus for Mining, of which the following is a full, clear, and exact description, reference being had to the accompanying drawings.

This application is a division of my former application, filed May 25, 1904, Serial No. 209,622, for a method of mining.

Figure 1 is a cross-section of an upraise or manway on a mineral vein from the main level of the underground workings. Fig. 2 is a top view of the upraise on the line II II of Fig. 1. Fig. 3 is a vertical section on the line III III of Fig. 1. Fig. 4 represents a side view, and Fig. 5 a front view, of the timber used as end pieces in constructing the upraise illustrated in Figs. 1, 2, and 3. Fig. 6 illustrates a side view, and Fig. 7 a plan view, of timbers used as side pieces in the upraise. Fig. 8 illustrates, partly in section, the metallic ore-chute shown in plan view in Fig. 2, as well as an adjustable telescopic hopper used at the top of the ore-chute as the upraise advances upward until a point has been reached where another section of metallic tubing can be attached. Fig. 9 is a plan view of the hopper on the top of the ore-chute with the tramway, ore-car, and man-

way or upraise. Fig. 10 is a cross-section of the metallic ore-chute. Fig. 11 is an elevation, partly in section, of the metallic ore-chute, illustrating the manner of securing together the various sections as they are placed in position in the upraise. Fig. 12 is a cross-section on the line XII XII of Fig. 11.

The object of my invention is to cheapen the cost of producing ore from mineral veins in shaft-mines in districts to which the apparatus is applicable.

Before actual mining commences I sink a working shaft, preferably to a great depth—say to two thousand feet, on which level all subsequent work is conducted until after all the mineral values have been extracted from all the veins that lie above that level, as stated below. When the work is conducted on the two-thousand-foot level, after the shafts have been completed a main double-track tunnel is cut that cross-cuts all veins from one limit of the property to the other. Whenever a mineral vein is reached and cross-cut by this main tunnel a branch tunnel in the drift from the main tunnel and on the level of the latter is driven on the vein itself. Thereafter all ore from the mineral vein is extracted from wall

to wall from the level of the main cross-cut tunnel upward continuously until the outcrop of the vein has been reached. As mining operations are thus conducted continuously upward in each separate drift, and preferably on each side of the main cross-cut tunnel, the floor is filled continuously around and over the outside of the arch of the drift-tunnel with a filling of suitable material throughout the entire extent of such drift to the property limits as rapidly as the ore is extracted from the vein overhead. In this manner it is intended that the difference between the level of the filling under foot and the level of the ore overhead shall be maintained at six, eight, or ten feet, as may be most convenient in removing the ore. In lieu of timbering I preferably use double-screw jacks and timber blocks to temporarily support the ore roof of the workings during mining operations, and these devices, while expensive in first cost, may be used continuously. The ore from each drift is dumped from tram-cars as mined into the metallic chute or chutes 2, Figs. 1 and 8 to 12, which are preferably located every two hundred feet on the drift continuously as the mining work progresses upward, and such ore is continuously withdrawn from the hopper or hoppers at the bottom of such chute below by the carman in the drift. The carman takes an empty car, pushes it by hand to one of the hoppers 3 at the bottom of the ore-chute 2, and fills it by gravity. He thereafter pushes it out onto the main line, after first placing in position the semaphore on the front of the car, which indicates whether it contains ore or waste material, and the car is then transported to the ore-pockets at the foot of the ore-hoisting shafts, into which its contents are automatically dumped. When the drift has been worked out and all of the mineral has thus been extracted from the vein completely to its top surface or outcrop or as close to the outcrop as the surrounding conditions render it safe to carry the mining operations, filling material is then packed solidly from the end of such drift at the utmost limit of the property-line, and such back filling is continued forward toward the main cross-cut tunnel. The tram-cars used in these underground workings are purposely made to unbolt, and each piece is of such size that it can be lowered in the car that travels up and down in the manway. In similar manner after all of the ore has been drawn out of the last metallic chute the upper hopper is removed in sec-

tions, and the metallic chute is also unbolted and lowered in sections, and the metal rungs on the manway-ladder are also then removed.

Fig. 1 shows a drift-tunnel, with its car and the receptacle or alcove 4 provided opposite the entrance to the upraise or manway for the storage of the small car that operates in the manway and which is used to hoist and lower drills, explosives, timbers from which the upraise is constructed, and anything else that may be desired. The figure also shows the tubular metallic ore-chute with the gate at the bottom thereof for loading a car with ore by gravity. From the top level of the vitrified brickwork as the upraise is carried upward by reason of the extraction of the ores and the subsequent filling twelve-inch timbers 5, cut to size at the mills, are used in the construction of the manway. These wooden pieces are simply set together, and wooden pins are driven through the corners. (This necessitates no timbermen and no carpenter-work. They are comparatively small, and can be made at sawmills in the western country from seraps and from waste lumber, so that they can be procured at much lower prices than ordinary mine-timbers can be bought for.) As each square of the timbers is placed in position and as the filling-work progresses upward specially-prepared iron or steel rungs 6 are driven into holes provided in the timber for that purpose. Thus the workmen pass to and fro through the same passage-way that is used by the hoist-car. This car may be hoisted and lowered by means of a hand-windlass, or preferably by a winch operated by compressed air. Where a serious deviation in the foot-wall occurs, as that shown in Fig. 1, two timbers 7 are placed so as to span it and to prevent too great a deviation in the angle of the upraise.

Fig. 2 illustrates the metallic ore-chute 2, air and water pipes, and the electric-light-wire and signal-wire conduits. It also illustrates a manway 2' and the ladder 8, on which the workmen pass up and down. A car passes up and down in the manway when it is in use. It also shows an ore-car in the drift-tunnel standing under the spout of the metallic ore-chute in a suitable position for loading, the manner of setting the wooden timbers of which the manway and ore-chute spaces are made, and the ore-car track in the drift-tunnel below.

Fig. 3 shows the upraise or manway with a car in position for loading under the spout of the ore-chute. It also illustrates the entrance to the manway and the tramway-track on which the car runs up into and down from the mine-workings through the manways.

Figs. 4 to 7 show the end pieces and side pieces of timber used in constructing the manways or upraises. These pieces are simply laid into their proper position on the upraise as the filling-work progresses, and wooden

pins are driven into place in corner-holes bored in the timbers at the mill.

Figs. 8 and 9 illustrate the sliding or telescopic adjustable ore-hopper 9 that is used at the top of the metallic ore-chute. They also illustrate an ore-car in position ready to dump ore into the chute while resting upon a section of the portable tramway. The metallic chute is preferably made in sections, and as mining-work and the filling in the drift progresses steadily upward and the square timber sets are continuously added extensible provision must be made at the top end of the metallic ore-chute until the upraise reaches a point where a new section may be added. This is provided for by the telescopic hopper, which is elevated from time to time as the filling progresses upward until a point has been reached where a new section of tubing may be added. The hopper is then again placed down in this new section, and it slides down telescopically thereon. The hopper is again elevated continuously upward, another section of tubing is added, and so the operation continues indefinitely. As each section of tubing is thus added provision is made in the upraise for securing it to the timbers and for holding it in its proper position. This is preferably accomplished by means of timber blocks or metal strips, as may be preferred. It will be understood that each section of tubing is only required to sustain its own weight and a part of the weight of the body of ore it may contain. A large proportion of the weight of the ore will be sustained by the gate-piece at the bottom, which is made of cast-iron and which rests on a foundation of vitrified brick.

Fig. 10 illustrates the mode of securing the tube on its side by bolts 10, which face toward the manway in order that they may be readily removed in case a section should wear out or in case of its final removal. It is intended that these ore-chutes shall be made of heavy sheets of plate-brass in order as far as possible to obviate the corrosive effects of the sulfate of copper. As these brass tubes wear out through the erosion of the ore that passes through them, the material is not lost or wasted. It passes, with the ore itself, into the smelter, and the copper thereof is thus recovered. In like manner, should a tube wear out from use it is removed, a new tube substituted for it, and the worn-out tube is thrown into the smelter or into the converter and its contained values thus in part recovered.

Fig. 11 shows my preferred mode of joining the sections of the tube. If a central section of the tube should wear out while in use, if the ore-chute were constructed with male and female joints one section could not be removed without involving the movement of and the emptying of ore from the entire chute. In order to prevent this inconvenience, I prefer to turn the end of each section around a me-

tallic ring 11, as illustrated, and thereafter to bolt a strap or yoke 12, having the form in cross-section of a segment of a circle, around the rings that constitute the ends of the two sections. The sections are thus bolted firmly together, and at the same time any section of the chute may be readily removed by workmen in the manway simply by removing two of the half-round clamps. Only so much of the ore in the chute as was above this one section need be drawn out through the gate below.

Variations will doubtless suggest themselves in the details of the apparatus without departing from the spirit of my invention, since

What I claim is—

1. Apparatus for mining comprising a manway and a metallic ore-chute therein; substantially as described.
2. Mining apparatus comprising an upraise, manway, or ore-chute, lined with a framework of timbers interlocked and set one upon the other, following substantially the contour of the vein; substantially as described.

3. Mining apparatus comprising a manway 25 having framework affording a ladder for operatives, and a track for a hoist-car in the same manway; substantially as described.

4. Apparatus for mining comprising in combination with a drift and upraise a metallic 30 ore-chute composed of superposed sections; substantially as described.

5. Apparatus for mining comprising in combination with a drift and upraise an ore-chute composed of superposed sections and a tele- 35 scopic hopper; substantially as described.

6. Apparatus for mining comprising in combination with a drift and upraise a metallic ore-chute composed of superposed sections clamped together and having the intermediate 40 sections removable; substantially as described.

In testimony whereof I have hereunto set my hand.

RALPH BAGGALY.
